UNITED STATES PATENT OFFICE

143,469

DESIGN FOR A DESK OR SIMILAR ARTICLE

Max Danziger, New York, N. Y.

Application September 13, 1945, Serial No. 122,073

Term of patent 14 years

(Cl. D33—7)

To all whom it may concern:

Be it known that I, Max Danziger, a citizen of the United States and resident of New York city, in the county of New York and State of New York, have invented a new, original, and ornamental Design for a Desk or Similar Article, of which the following is a specification, reference being had to the accompanying drawing, forming a part thereof, and of which Fig. 1 is a view in front elevation of a desk or similar article showing my new design; Fig. 2 is a view in side elevation thereof; and Fig. 3 is an enlarged sectional view taken on line 3—3 of Fig. 2.

The dominant features of my design consist in the portions shown in full lines.

The rear side and the other end of the desk are substantially the same as illustrated.

I claim:

The ornamental design for a desk or similar article, substantially as shown and described.

MAX DANZIGER.
